[57] CLAIM

I claim the ornamental design for a chest pack strap system, as shown, and described.

DESCRIPTION

FIG. 1 is a front perspective view of a chest pack strap system showing my new design;

FIG. 2 is an enlarged front view thereof;

FIG. 3 is an enlarged rear view thereof;

FIG. 4 is a front view on a reduced scale shown in a condition of use on a person; and,

FIG. 5 is a rear view on a reduced scale shown in a condition of use on a person.

The broken line showing of environment in FIGS. 1-5 is for illustration purposes only and forms no part of the claimed design.
